GARMENT PATTERN DRAFTING STENCIL

Camille Albert Ajus and Marguerite Nicholas Ajus, both of 910 Lamer, Apt. 5, St. Laurent, Quebec, Canada

Filed May 13, 1971, Ser. No. 143,277

Term of patent 14 years

Int. Cl. D19—06

U.S. Cl. D52—6 A

FIG. 1

FIG. 2

FIG. 1 is a front plan view of the garment pattern drafting stencil embodying the design of the present application; and

FIG. 2 is a back plan view of the article of FIG. 1.

The garment pattern drafting stencil comprises sheet material of no appreciable thickness.

We claim:

The ornamental design for a garment pattern drafting stencil, as shown and described.
